(57) **CLAIM**

The ornamental design for a sign kiosk assembly, as shown and described herein.

DESCRIPTION

The sign kiosk assembly of the present invention is intended for use as a point of purchase advertising display for any retail location, such as, fuel stations, supermarkets and the like.

FIG. 1 is a front perspective view of the sign kiosk assembly according to a preferred embodiment of the present invention; and,

FIG. 2 is a back perspective view of the sign kiosk assembly of FIG. 1.

The broken line lettering shown on FIGS. 1 and 2 are for illustrative purposes only and forms no part of the claimed design.

1 Claim, 2 Drawing Sheets

FIG. 1

FIG. 2
